Attorneys

UNITED STATES PATENT OFFICE.

EUGENE W. WILSON, OF SPRINGFIELD, ILLINOIS.

PACKAGE.

1,254,755.

Specification of Letters Patent. Patented Jan. 29, 1918.

Application filed June 7, 1915. Serial No. 32,509.

To all whom it may concern:

Be it known that I, EUGENE W. WILSON, a citizen of the United States of America, residing at Springfield, in the county of Sangamon and State of Illinois, have invented certain new and useful Improvements in Packages, of which the following is a specification, reference being had therein to the accompanying drawings.

10 My invention relates to packages and more particularly to packages for eggs or other fragile articles.

The invention has among the objects thereof to produce a package in which independent seats are provided that will hold the articles out of contact with each other; to provide such a package in which the seats for the articles are yielding so as to avoid, to a material extent, shocks being transmitted to the articles, the seats however, having sufficient rigidity to prevent the articles from coming in contact with one another; to provide a package in which the seats will, within certain limits, readily adapt themselves to articles of varying sizes; to provide a sectional package, the sections of which may be readily assembled or taken apart; and further, to provide a package which is water-proof and which will prevent any liquid accidentally discharged into the package from the articles therein, from leaking out of the package. Other objects of the invention will more fully hereinafter appear.

35 The invention resides in the peculiar construction, arrangement and combination of parts as will be hereinafter set forth and particularly pointed out in the claims.

40 While a package embodying the invention is adapted for other uses, as it is particularly designed for eggs, I will illustrate and describe the invention as embodied in a package for eggs.

In the drawings,—

45 Figure 1 is a central, vertical section through a package embodying the invention; Fig. 2 is a section on the line $x-x$ of Fig. 1; and

Fig. 3 illustrates a modification.

50 Referring to the structure shown in Figs. 1 and 2, A designates a receptacle, preferably formed of metal, the receptacle being herein shown as cylindrical and having a bottom B formed integral with the sides C and provided with a removable closure D. Within the receptacle are a plurality of

trays E. These trays are preferably formed of metal and are spaced from one another. The peripheries of the trays E are provided with annular flanges F and each of the trays is centrally apertured to engage over a bolt G that extends from top to bottom of the receptacle. The trays are each provided with an annular flange H surrounding the aperture. The flanges F and H form spacers for the trays, as will be readily apparent upon reference to Fig. 1. The cover D is positioned within the plane of the top of the receptacle and has an annular flange I acting both to position the cover within the sides and also to form a tight joint between the sides and the cover. J is a nut on the upper end of the bolt G and by tightening this nut the trays will be clamped rigidly within the receptacle. Preferably the bottom B of the receptacle is provided with a struck-up portion K of sufficient size to receive the head L of the bolt so as to position the head L within the plane of the bottom of the receptacle.

55 In the structure shown in Figs. 1 and 2, the trays are preferably formed of imperforate metal except for the central apertures. The seats for the eggs are formed by opposed sockets. Thus as shown, upon each face of each of the trays is secured a layer of yielding material M, preferably rubber, which has formed therein a plurality of sockets N. These sockets are shaped to fit the article and when employed for receiving eggs, are cup-shaped and preferably slightly tapered. The walls O of the socket while sufficiently yielding to conform to the contour of the egg, are nevertheless sufficiently firm to properly hold eggs that do not completely fill the socket. This permits eggs of various sizes to be indiscriminately arranged upon the trays.

60 Assuming the parts are arranged as shown in Fig. 1, when it is desired to remove one or more trays the nut J is removed and the cover D withdrawn. The trays with the eggs thereon can then be lifted out of the receptacle as desired. While the seats for the eggs are formed by oppositely-extending sockets upon adjacent trays, the sockets upon the upper face of the trays—that is, the upwardly-extending sockets—are of sufficient depth to support the eggs when the tray having the downwardly-extending sockets is removed.

65 Since the receptacle A is formed of im-

perforate metal and since the cover D also is imperforate, not only is the receptacle water-proof but also is such as to prevent any liquid material leaking out of the package in case any of the eggs become broken.

In the structure shown in Fig. 3, the receptacle and the arrangement of the trays are the same as that described in connection with Figs. 1 and 2. The trays P however 10. are provided with a plurality of apertures Q of a size slightly larger than the ends of the eggs. Secured over the face of the trays is a sheet of yielding material R, preferably fabric such as canvas covered with rubber. 15 This sheet is provided with apertures S of a size less than the size of the apertures in the tray, so as to engage and hold the egg out of contact with the sides of the apertures in the tray. Preferably as shown the edges 20 T of the apertures in the sheet and the edges U of the apertures in the tray have tapering flanges.

In the structure shown in Fig. 3, instead of the sockets for adjacent layers of eggs 25 being secured to opposite sides of the tray, as in the structure shown in Fig. 1, a separate tray is employed for each series of sockets.

Not only does the package embodying the 30 invention provide a very durable structure

and one that may be readily assembled or taken apart, but also the articles are properly held in any position of the package. Thus it is immaterial whether the package is turned wrong side up or rolled upon its 35 side, since the seats will at all times hold the articles against coming in contact with one another.

While I have shown the invention as embodied in a cylindrical package, the shape of 40 the package may be varied as desired.

What I claim as my invention is:—

1. In a package, a tray comprising a sheet metal member, a metallic spacing element rigidly carried by said member and sheets of 45 resilient material secured to opposite faces of said sheet metal member and respectively formed with a plurality of pockets.

2. In a package, a tray comprising a sheet metal member formed with a peripheral 50 flange, and a layer of rubber upon each face of said sheet formed with a plurality of article receiving sockets.

In testimony whereof I affix my signature in presence of two witnesses.

EUGENE W. WILSON.
